UNITED STATES PATENT OFFICE.

JOHN J. GAYNOR, OF INDIANAPOLIS, INDIANA, ASSIGNOR TO MEIER-GAYNOR MANUFACTURING CO., OF INDIANAPOLIS, INDIANA, A CORPORATION OF INDIANA.

BOTTLE CROWNER.

Application filed July 5, 1919. Serial No. 308,806.

To all whom it may concern:

Be it known that I, JOHN J. GAYNOR, a citizen of the United States, residing at Indianapolis, in the county of Marion and State of Indiana, have invented a new and useful Bottle Crowner, of which the following is a specification.

It is the object of my invention to provide a simple and effective crowning mechanism, for attaching bottle crowns to bottles.

The accompanying drawings illustrate my invention: Fig. 1 is a perspective view of a crowner equipped with crowning mechanism embodying my invention and with a crown feeder for placing the crowns on the bottle mouths; Fig. 2 is a vertical section through the crowner, to show the action of the feeding and crowning mechanism, being taken substantially on the line 2—2 of Fig. 3; Fig. 3 is a horizontal section, substantially on the line 3—3 of Fig. 2; and Fig. 4 is an enlarged vertical section through the lower end of the crowning head, showing it in co-operation with a bottle mouth.

25 A bottle-supporting table 10 is carried by a pedestal 11 suitably supported on a base 12. Three vertical shafts 13, 14, and 15 project through this bottle-carrying table 10, and below such table are provided with 30 intermeshing gears 16, 17, and 18 respectively, which gears mesh to drive the shafts 13 and 15 in the same direction and the shaft 14 in the opposite direction. The shaft 13 is connected by bevel gearing 19 to 35 a horizontal driving shaft 20 mounted in the pedestal 11 and driven in any convenient manner, as by an electric motor 21 mounted on a platform 22 suitably supported from the base 12, said motor being connected to 40 the shaft 20 by a belt 23 and suitable pulleys.

The shafts 13 and 15 are provided with bottle-carrying disks 25 and 26, the upper surfaces of which are flush with the upper surface of the table 10; the disk 26 is a 45 heavy disk, as it carries the bottle during the crowning operation, and is preferably provided with a hard rubber plate 27 set in its upper surface on which plate the bottle stands while it is being crowned. The shaft 14 is provided above the table 10 with 50 two transverse members 28 and 29, of any suitable shape, for engaging the side of a bottle near bottom and top and carrying the

bottle from the disk 25 to the disk 26 over the surface of the table 10 and beneath a 55 crown chute 30 from which the bottle receives a crown. The bottles are guided in their travel by suitable fixed partitions 31, 32, and 33, shown in plan in Fig. 3. The bottles are fed on to the table 10 in any suitable way between the partitions 31 and 32, and guided thereby on to the disk 25; which carries them in a counterclockwise direction into position to be engaged in notches 34 and 35 on the transverse members 28 and 29; 60 which members in turn slide the bottles onward over the table 10 in a clockwise direction about the shaft 14 and in constant engagement with the guiding partition 32 so that the bottles pass beneath the chute 30 65 and on to the disk 26; which carries them in a counterclockwise direction while the crowning operation takes place and delivers them crowned on to the table 10 and into a pocket formed by the partition 33, the 70 two ends of which project over the disk 26 to guide the bottles into such pocket. The partitions 31 and 32 and the shoulder 34 may be provided with detachable plates suitably mounted on the main members of which 75 they form part so that the machine will accommodate different sizes of bottles.

The travel of the bottles on the disk 25 is controlled by a stop 40, which is a finger mounted on a pivot post 41 and spring-pressed by a tension spring 42 in a clockwise direction toward the position shown, where it stops the passage of the bottles. This stop 40, however, has a laterally projecting operating arm 43, which is engaged 80 by pins 44 on the transverse member 28 so as to turn the stop 40 against its spring 42 to release a bottle and allow it to pass on with the disk 25. The release of a bottle is timed, by the position of the pins 44 and 95 the length of the arm 43, so that it allows the bottle to be carried forward in proper time to be engaged by the approaching shoulders 34 and 35. In order to get this timing properly, a leaf spring 45 is provided to hold the bottles toward the center of the disk 25 so that the time of their release by the stop 40 may have an exact relation to the movements of the shaft 14.

The chute 30 is supplied with crowns from 105 a hopper 50, from which the crowns are

fed to the chute by any suitable mechanism operated by a pulley 51 driven by a belt 52 from a pulley 53 on one end of a horizontal shaft connected by bevel gearing 54 to the upper end of the vertical shaft 15.

The crown-feeding mechanism shown, whereby the crowns are removed from the chute 30 and deposited on the mouth of a bottle in position for the crowning operation, forms, per se, the subject-matter of my co-pending application Ser. No. 308,808, of even filing date herewith. Though other crown-feeding mechanism may be used, such for instance as shown in my co-pending application, Ser. No. 308,807, of even filing date herewith, an understanding of the mechanism illustrated is desirable in connection with the present application.

The chute 30 is vertical, and the crowns therein are in line one above the other, and rest upon one another, as is clear from Fig. 1. At its lower end, the chute 30 is provided with a swinging plate 55, mounted on a horizontal pivot pin 56 and forming the wall of the chute on the side from which the bottles approach the chute; and this plate 55 is provided with vertical flanges which form the edge walls of the chute near the bottom thereof. The wall of the chute opposite the plate 55 is rigid with the body of the chute, and separate from the plate 55. The latter is spring-pressed toward the opposing wall of the chute, so that normally such plate and the edge flanges thereof constitute merely a continuation of the corresponding walls of the upper part of the chute; but this plate 55 may be swung against its spring, to separate it from its opposing wall. The lower end of the chute is provided with means for holding the lowermost crown with its lower segment projecting downward out of the chute in position to be engaged by the side of the bottle mouth as the bottle travels beneath the chute, so that upon such engagement and the continued movement of the bottle the lowermost crown is tilted to throw its upper edge against the plate 55 and force the latter against its spring until the lowermost crown is released from the chute and dropped onto the mouth of the bottle which is tilting it. A pair of arms 61 project obliquely downward from the chute 30 on the side thereof from which the bottles approach the chute, and pivoted to their lower ends is a plate 63 which projects from its pivotal point past the chute 30, being provided with an opening through which said chute extends. This plate is spring-pressed downward, by a leaf-spring 64. The plate 63 is curved to conform to the path of travel of the bottles, and rides upon the crowns which are placed on the bottles as they pass beneath the chute 30 and holds such crowns in place. The plate 63 may be provided

with downwardly projecting flanges to form guides for the edges of the crown on the bottle.

After the crown is thus placed on top of the bottle mouth as described, the bottle continues its forward movement under the pushing action of the members 28 and 29, and is carried thereby onto the disk 26. Here it is taken from the notches 34 and 35 by two pushing fingers 70 and 71, which are mounted on the shaft 15 in position to engage the bottle near bottom and top. The fingers 70 and 71 hold the bottle on the hard rubber plate 27, in position for the crowning operation. A leaf-spring 73 bears against the side of the bottle as it passes from the members 28 and 29 to the fingers 70 and 71, and assists the latter in positioning the bottle on the hard rubber plate 27, for the crowning operation.

The shaft 15 carries the crowning mechanism, for clamping on the mouth of the bottle the crown which was deposited thereupon as the bottle passed beneath the chute 30. This crowning mechanism, the shaft 15, the disk 26, the fingers 70 and 71, and the bottle all rotate together, with the bottle and the crowning mechanism in vertical alignment, and the crowning operation takes place as they move.

This crowning mechanism comprises a vertically movable crowning head 75, which is carried by a sleeve 76 splined on the shaft 15; and this crowning head is provided with a lifting roller 77 which co-operates with a stationary lifting cam 78 to raise the head during one part of the rotation of the shaft 15, and with a depressing roller 79 which at one point in the rotation of the shaft 15—the point of maximum compression and the low point of the cam 78—passes beneath a roller 80 on the end of a pivoted arm 81 spring-pressed downward by an adjustable compression spring 82 acting on the arm 81 through a rod 82' pivotally connected thereto. The head 75 is provided at its lower end with a removable throat member 83 having a cone-shaped throat or opening therethrough, which throat engages the corrugated edge of the crown on the bottle and crimps such edge inward beneath the head at the bottle mouth. Within this crowning head 75 there is a compressing plunger 84, which is spring-pressed downward within such head by a spring 85 but may be pushed upward within said head as the latter descends until a collar 86 thereon engages a shoulder 87 on the interior of the crowning head to produce a positive compressing action.

As the bottle passes onward toward and to the disk 26, after having received its crown, it carries its crown with it, and the crown is continuously engaged and held in place on the bottle by the downwardly

pressed plate 63, which is curved to conform to the travel of the bottle; and as the shaft 15 rotates, the head 75 is started on its downward movement before the crown on the bottle passes out of engagement with the plate 63, so that as during the onward movement of the bottle the crown passes out from under the plate 63 it is engaged by the lower end of the compressing plunger 84 and held in place. Immediately following this engagement by the plunger 84, the continued forward movement of the shaft 15 and its associated parts causes the head 75 to continue its descent and the conical throat 83 in such head to engage and crimp inward the edge of the crown, while the downward pressure of the plunger 84, which pressure at the last is a positive pressure by reason of the engagement of the collar 86 and shoulder 87, compresses the cork lining of the crown to make an air-tight closure of the bottle. This air-tight closure is maintained permanent because the compression of the cork lining is maintained by the locking action of the crimped edge of the crown around the bead at the bottle mouth. The final compressing and crimping action occurs as the roller 79 passes beneath the roller 80, and the degree of compression of the cork lining is controlled by the adjustment of the spring 82. The roller 77 separates from the cam 78 during this final action, to allow the free action of the spring. After the crowning is complete, the cam 78 lifts the head 75 so that such head and the plunger 84 are separated from the crowned bottle; and the crowned bottle is carried by the rotating disk 86 into the opening between the ends of the partition 33 and delivered into the pocket for the crowned bottles, which may be removed from such pocket as desired.

The normally stationary parts, such as the cam 78, the hopper 50, and the chute 30, are vertically adjustable for different heights of bottles. To this end, they are all carried by a vertically adjustable frame 90, which is provided with two sleeves 91 vertically slidable on two vertical screws 92, on which there are hand-wheel nuts 93 engaging such sleeves 91 at top and bottom to produce such vertical adjustment. The bevel gearing 54 is also carried by this frame 90, and on account of this vertical adjustment that bevel gear of such gearing which is on the shaft 15 is splined on such shaft. By manipulating the nuts 93, the apparatus may be adjusted for any desired height of bottle. This is the only adjustment required, as the vertical adjustment of the cam 78 determines the height at which the crowning head operates.

By the term "bottle" I intend to include any suitable container, and not to limit myself to containers with necks and mouths smaller than their bodies; and by the term

"crown" I intend to include other covering and capping devices than those with corrugated edges.

I claim as my invention:

1. A crowning mechanism for bottles, comprising a vertical rotatable shaft, a bottle supporting member and a crowning head rotatable with said shaft and movable relative to each other longitudinally, said head including a conical throat for engaging and crimping inward the corrugated edge of a crown of a bottle, and a plunger mounted within said head and engaging the top of said crown prior to its engagement with said conical throat, a crown chute having means in the path of the bottle as it passes to the crowning head and in advance of said head for applying the crown to the bottle while the bottle is moving, and means for holding said crown on said bottle after it is applied by said means and until it is engaged by the plunger of the crowning head.

2. A crowning mechanism for bottles, comprising a vertical rotatable shaft, a bottle supporting member and a crowning head rotatable with said shaft and movable relatively to each other longitudinally, said head including a conical throat for engaging and crimping inward the corrugated edge of a crown of a bottle and a plunger mounted within said head and engaging the top of said crown prior to its engagement with said conical throat, means in the path of said bottle as it passes to the crowning head and in advance of said head for applying the crown to the bottle while the bottle is moving, and means for holding said crown on said bottle after it is applied and until it is engaged by the plunger of the crowning head.

3. A crowning mechanism for bottles, comprising a vertical rotatable shaft, a bottle supporting member and a crowning head rotatable with said shaft and movable relative to each other longitudinally, said head including a conical throat for engaging and crimping inward the corrugated edges of a crown of a bottle and a plunger mounted within said head for engaging the top of said crown prior to its engagement with said conical throat, a crowning chute in the path of said bottle as it passes to the crowning head and in advance of said head having means for applying the crown to the bottle while the bottle is moving, means for holding said crown on said bottle after it is applied and until it is engaged by the plunger of the crowning head, and means for vertically adjusting said chute and crowning head to accommodate different heights of bottles.

4. A crowning mechanism for bottles, comprising a vertical rotatable shaft, a bottle supporting member and a crowning head

5 rotatable with said shaft and movable relative to each other longitudinally, said head including a conical throat for engaging and crimping inward the corrugated edge of the 10 crown of a bottle, and a plunger mounted within said head for engaging the top of said crown prior to its engagement with said throat, means in the path of said bottle as it passes to the crowning head and in advance of said head for applying the crown to the bottle while the bottle is moving, means for holding said crown on said bottle after it is applied and until it is engaged by the plunger of the crowning head, and means 15 for adjusting said holding means and the crowning head vertically to accommodate different heights of bottles.

5. A crowning mechanism for bottles, comprising a vertical rotatable shaft, a bottle 20 supporting member and a crowning head rotatable with said shaft and movable rela-

tive to each other longitudinally, said head including a conical throat for engaging and crimping inward the corrugated edge of the crown of a bottle and a plunger mounted 25 within said head engaging the top of said crown prior to its engagement with said throat, means in advance of said head and in the path of said bottle for applying the crown to the bottle while the bottle is moving, means for holding said crown on said bottle after it is applied and until it is engaged by the plunger of the crowning head, and means for simultaneously adjusting said holding means and said crowning head to 30 35 accommodate the same to bottles of different heights.

In witness whereof, I have hereunto set my hand at Indianapolis, Indiana, this 19th day of June, A. D. one thousand nine hundred and nineteen.

JOHN J. GAYNOR.
